TUBULAR MAGAZINE FIREARM WITH LOADING PORT IN SIDE OF MAGAZINE

Paul A. La Violette, Jr., Hamden, Conn., assignor to The High Standard Manufacturing Corporation, Hamden, Conn., a corporation of Connecticut

Filed Oct. 20, 1959, Ser. No. 847,494

2 Claims. (Cl. 42—6)

This invention relates to an improvement in the loading of tubular magazines for automatic, semi-automatic and manually operated firearms and in particular to means for facilitating rapid loading of such magazines.

At present a tubular magazine may be loaded by inserting cartridges by hand or by use of a charging device through a loading port in the underside of the magazine or through the open end of the magazine. The usual procedure for loading through a port in the underside of the magazine involves turning the firearm upside down so as to expose the loading port of the magazine and withdrawing a spring-loaded inner magazine tube past the loading port. With the firearm held in one hand, cartridges are inserted by the other hand one at a time into the loading port. Usually the hand which inserts the cartridges into the magazine, is filled with as many cartridges as it will hold. Each cartridge must be selected by means of the fingers of the same hand which holds them and then properly positioned in the loading port so that it will drop into the magazine. The procedure is substantially the same when loading is done through the forward end of the magazine except that the inner magazine tube has to be completely withdrawn. In either case the loading procedure is cumbersome and slow, considerable difficulty being experienced when loading is done hurriedly or with cold fingers.

Up to the present time no simple, inexpensive mechanical device or arrangement has existed which facilitates the quick, easy loading of a tubular magazine. It is therefore a primary purpose of this invention to provide a unique construction and arrangement of the magazine and barrel whereby the disadvantages of previously available apparatus can be avoided.

Magazine charging devices have of course been developed in an attempt to facilitate the loading of tubular magazines. However, such a device constitutes a separate and distinct piece of equipment which is usually designed to contain and dispense a cartridge of a particular size. When a charging device is used, quick loading is undoubtedly effected. But the practicability of such a device is, for the most part, limited to shooting galleries and the like where the marksman is supplied with loaded firearms or with several charged magazine tubes for each gun. In such cases the rifles are usually all of the same caliber, thus permitting the use of the same devices for loading all the guns. Under these circumstances, the unimportance of the additional weight of and space taken by the charging devices, the danger of loading by hand in public places and the convenience of the customer all amply justify the use of charging devices.

On the other hand, for certain types of shooting, such as hunting and game shooting, charging devices offer little or no advantage and, in fact, can be distinctly undesirable. For example, the weight and bulk of hunting equipment which must be kept to a minimum are further increased by the use of magazine charging devices. Furthermore, devices of this kind constitute an additional expense which is further increased where the charging device requires a modification of the magazine. But even more important than this, if the charging devices need to be reloaded by the shooter while he is hunting, he might as well fill the magazine directly as to reload the charging devices, because refilling the magazine directly

2

is no more difficult, and may be easier, than reloading the charging devices under these conditions. Therefore, considering the disadvantages of added bulk, weight and expense which magazine charging devices entail, an important object of my invention is to provide a magazine which can be loaded quickly and easily without the use of charging devices.

In brief, the invention involves locating the cartridge loading port of a tubular magazine so that it is substantially in the trough formed by the barrel of the gun and the magazine, such trough forming a track or ramp along which the cartridge can be guided into the loading port. Thus, since it has heretofore been impractical for one reason or another to provide positive means by which to guide each cartridge one-by-one into the loading port, the mere manipulation of a cartridge to insert it into the magazine has been rather tedious and irritating. This is due to the fact that the loading port has invariably been located in the underside of the magazine tube directly opposite the barrel or at the end of the magazine and can be located only roughly by eye and then guided into the port by the touch of the fingers. Even then it is frequently necessary to shift the cartridge both laterally and longitudinally in order to get it lined up properly with the port. This is even more time consuming and tedious when the hands are cold or when gloves are worn.

The present invention virtually does away with all fumbling and awkwardness of this kind by providing a positive guide for the cartridges into the port, this being accomplished without increasing the expense of the magazine in the slightest or, for that matter, without even the need of additional parts or manufacturing operations. The invention therefore overcomes, wholly or in large part, the disadvantages and difficulties which have attended the various loading methods and procedures used heretofore and accomplishes this in a manner which is simple, effective and economical.

Other objects and advantages of the invention will be apparent from the following detailed description of a practical embodiment of the invention, reference being had to the accompanying drawings, in which —

FIG. 1 shows a rifle having a tubular magazine construction arranged and positioned in accordance with the invention and illustrating how the cartridges are guided between the adjacent surfaces of the barrel and magazine into the loading port;

FIG. 2 is a side elevation, partially broken away and partially in section, of the barrel and magazine of a firearm embodying the invention;

FIG. 3 is an enlarged detail view in side elevation showing the cartridge loading port; and

FIG. 4 is a transverse sectional view taken on line 4—4 of FIG. 3 showing the position of the cartridge loading port with respect to the underside of the rifle barrel.

Referring to the drawings, FIG. 1 shows a rifle 10 with a stock 11, barrel 12, tubular magazine 13 and cartridge loading port 14. The component parts of the loading and firing mechanism have not been shown since 60 any one of a number of different actions might be used.

The tubular magazine 13, which is basically conventional in construction, comprises an outer tube 15, and an inner tube 16 fitting within the open end of the outer tube for telescoping movement into and out of tube 15.

65 A pin 17 and slot 18 at the front ends of the magazine tubes are provided for securing them together when fully telescoped. The inner tube carries a cartridge follower and spring 19 which urge the cartridges in the magazine rearwardly toward the receiver 20 of the gun. Magazine 70 13 is positioned along the underside of the barrel 12 so that the longitudinal axes of the tube and barrel are substantially parallel, with the rear end of magazine 13 ex-

tending into receiver 20. The forward end of the outer tube 15 of magazine 13 is supported and secured to the barrel by a bracket 21 while the rear end is fixed in a bracket 22 in a manner which will be described hereinafter.

In order to load magazine 13, inner tube 16 is unlocked by rotating it so that its locking pin 17 moves into the longitudinal portion of slot 18, and tube 16 is then drawn forwardly out of the outer tube 15 until the cartridge follower (not shown) is forward of loading port 14, all in accordance with the conventional practice. Cartridges 23 can then be inserted into loading port 14. Cartridge loading port 14 is shaped in the usual manner so as to preclude insertion of the cartridges through it in the wrong direction. Thus, the width of port 14 is greater than the diameter of the body of a cartridge 23 but is slightly less than the diameter of the rim of the cartridge. Port 14 is also cut away at its rear end on both sides at 24 to permit the rim of the cartridges to pass when located properly with respect to loading port 14. As each cartridge is inserted through port 14 into magazine 13, it slides rearwardly by gravity, the gun being held with the muzzle pointed upwardly in order to effect this. When as many cartridges as the magazine will hold have been inserted, the inner tube 16 is telescoped rearwardly around the cartridges within tube 15, compressing follower spring 19 so that the column of cartridges within magazine 13 is urged rearwardly toward the receiver in order to feed the cartridges one-by-one into the loading mechanism (not shown).

It will be noted from the drawings that the outer surfaces of barrel 12 and magazine 13 form between them a kind of guide-trough 25 extending axially of the gun, in which one or more cartridges to be loaded into the magazine can be cradled as illustrated in FIGS. 1, 3 and 4. The present invention involves the positioning of the magazine close enough to the barrel so that this trough may act as a guide or ramp by preventing cartridges of given size from passing between the barrel and magazine, and in positioning the loading port substantially in said trough such that the latter positively guides and directs the cartridges into the loading port.

To this end, cartridge loading port 14 is formed in the side wall of the outer tube 15 so that it obliquely faces barrel 12, thereby opening into trough 25 as illustrated in the drawings. As a result of the proximity of port and trough, the cradled cartridges 23, if placed in a row along trough 25 as shown in FIG. 1, can be shifted longitudinally into lateral alignment with port 14 so that they will drop one by one through the port and into magazine tube 14. It will be seen, therefore, that the position of cartridge loading port 14 with respect to the underside of the barrel and the trough is of the utmost importance in this invention. In what is at present regarded as the best practical embodiment of the invention, port 14 is positioned so as to allow the cartridge when shifted into lateral registry with the port to drop from its cradled position in the trough into the magazine without requiring lateral manipulation on the part of the loader. This is accomplished by locating the center line of port 14 in a plane, represented by the line *ab* in FIG. 4, passing through the longitudinal axes of magazine 13 and of a cradled cartridge 23. However, accurate alignment of the loading port in this manner is not essential so long as the port is in a position where the cartridge will readily pass through port 14 when in lateral registry therewith in trough 25.

In the arrangement shown in FIGS. 3 and 4, one cartridge is shown as if held in trough 25 by means of the fingers rather than in a column as shown in FIG. 1. Since loading port 14 is here located directly in line with cartridge 23, the rim of the cartridge will drop somewhat into port 14 when it reaches the forward part of port 14 as the cartridge is shifted rearwardly to bring it into lateral registry with the port. Since port 14 is narrower than

the rim of the cartridge, the cartridge can not drop into the magazine tube until the rim reaches the cut-aways 24 at the rear of port 14. Since part of the periphery of the head of the cartridge drops below the outer surface of magazine tube 15 before the rim moves into registry with cut-aways 24, the rear end of port 14 acts as a stop to prevent any possibility of a cartridge being shifted so rapidly along trough 25 that its rim could go on past the cut-aways 24 without permitting the cartridge to drop through.

Even if port 14 is not exactly centered with respect to the cartridges in trough 25, there is a tendency for the head of the cartridge to twist or shift laterally toward the port as the cartridge is moved along port 14 so that the cartridge rim usually is guided between the longitudinal edges of the port before it reaches the cut-aways 24. However, if the port is for one reason or another located so far out of line that the rim of the cartridge does not drop into engagement with both sides of port 14 as it is moved rearwardly along the port, the cartridge rim will nevertheless ordinarily catch in the adjacent cut-away 24 whereupon the cartridge can then be readily shifted laterally into position directly over the port so that it will pass through into the magazine.

The appropriate position of the loading port with respect to the trough 25 for the cartridge to move, unobstructed, into magazine 13 can be determined by reference to the angular relationship which exists between the cross-sectional center line *ab* of the loading port 14 and the center line designated *ac* common to both the barrel 12 and magazine 13. In FIG. 4 this angle is designated as *x*, its magnitude in any particular model of firearm for providing the most satisfactory position of the cartridge loading port depending on the outside diameters of the gun barrel and magazine tube, as well as on the diameter of the cartridge and the distance between the longitudinal axes of the barrel and magazine. It is of course necessary in order to satisfactorily carry out the present invention to locate the magazine with respect to the barrel so that the space between them is not greater than the diameter of the cartridge used. On the other hand, the magazine may, if desired, engage the barrel so long as a trough is formed between them in which cartridges can be cradled in accordance with the present invention.

In assembling the magazine tube 15 on the barrel 12, it is of course important to be sure that loading port 14 is properly positioned with respect to trough 25. To this end, tube 15 is provided with an aperture 26 adjacent its rear end at the point where it is supported in the rear mounting bracket 22. Bracket 22 has a hole 27 of the same size as aperture 26 in tube 15 drilled in its under side, while a recess 28 is formed in its inner surface opposite hole 27. By positioning aperture 26 of magazine tube 15 in registry with the hole 27 of bracket 22, a pointed tool (not shown) having a shank the same size as holes 26 and 27 can be inserted through said holes in order to deform the upper side of tube 15 into recess 28, thereby staking it in place. Aperture 26 must of course be in proper angular relationship with the loading port 14 in order to make the foregoing assembly operation possible. This is readily determined by the angle *x* (FIG. 4) referred to hereinbefore.

The most desirable position in which to hold the rifle while loading is tilted sideways so that loading port 14 is facing upwardly. In this position, trough 25 will cradle cartridges 23 as shown in FIG. 1. With the inner tube 16 withdrawn from the outer tube 15 beyond the cartridge loading port 14, the cartridges can be shifted longitudinally in trough 25, through loading port 14, into magazine 13. Where feasible several cartridges can be lined up in trough 25 in a column and then moved rearwardly into port 14 either manually or by simply lifting the muzzle of the gun so that they slide by gravity. On the other hand, it is also easy to load the magazine even if it is

necessary to hold the rifle with port 14 facing down. In that event the cartridges are pressed upwardly by means of a person's fingers against trough 25, slid longitudinally into registry with port 14 and then pressed upwardly through said port. In any of the various ways in which the present magazine can be loaded, it is of course desirable to have the muzzle of the gun pointed upwardly enough to make each of the cartridges slide rearwardly in magazine 13 as soon as it passes through port 14 so that the succeeding cartridge can enter the magazine. When the magazine 13 has been loaded, the inner tube 16 is returned to its fully telescoped position within outer tube 15 and secured in place by manipulation of the locking means provided therefor.

In the foregoing description of a certain specific manner of carrying out the invention, reference has been made to a rifle since the loading of this type of firearm is very easily and quickly accomplished by means of the present invention notwithstanding the problems of size and weight peculiar to this type of firearm. It is to be understood, however, that the invention is not limited entirely to rifles.

What is claimed is:

1. In a tubular magazine type of firearm, the combination comprising a barrel, a magazine tube adjacent said barrel and extending substantially parallel thereto, said barrel and magazine tube forming between their outer

surfaces a trough capable of receiving and longitudinally guiding cartridges to be loaded into said magazine tube, a wall of said magazine tube having a cartridge loading port opening into said trough whereby cartridges cradled in said trough are positively guided between said barrel and magazine tube substantially into said loading port.

2. In a tubular magazine type of firearm, the combination comprising a barrel, a magazine tube secured to the underside of said barrel extending substantially parallel thereto, said barrel and magazine tube forming between their outer surfaces a trough capable of receiving and longitudinally guiding cartridges to be loaded into said magazine tube, a wall of said magazine tube having a cartridge loading port elongated longitudinally of said magazine and opening into said trough whereby cartridges cradled in said trough are positively guided between said barrel and magazine tube substantially into said loading port.
